UNITED STATES PATENT OFFICE.

ERASTUS E. WINKLEY, OF LYNN, MASSACHUSETTS.

SOLE-PRESSING MACHINE.

No. 818,503.

Specification of Letters Patent.

Patented April 24, 1906.

Application filed October 23, 1900. Serial No. 34,011.

To all whom it may concern:

Be it known that I, ERASTUS E. WINKLEY, a citizen of the United States, residing at Lynn, in the county of Essex and State of Massachusetts, have invented certain new and useful Improvements in Sole-Pressing Machines; and I do hereby declare the following to be a full, clear, and exact description of the invention, such as will enable others skilled in the art to which it appertains to make and use the same.

The present invention relates to sole-pressing machines including that class of machines known in the art as "sole-laying" machines, by which the outsole is attached to the lasted upper and insole of a shoe and made to conform to the contour of the bottom of the last preparatory to its permanent attachment by means of stitching or otherwise, and also including that class of machines known in the art as "sole-leveling" machines, by which the outsole after having been permanently attached to the shoe is subjected to pressure to give it the proper shape or curvature.

The present invention relates more particularly to sole-pressing machines of either of the above-mentioned classes of the so-called "direct-pressure" type, in which the shoe-sole is subjected to pressure between a suitably-shaped form and a jack upon which the shoe is supported.

In direct-pressure sole-pressing machines as heretofore constructed means have been provided for relatively actuating the jack and form to bring the jack into a position to allow the removal of a shoe previously acted upon and the adjustment of another shoe thereon, said position being a position of presentation, and for bringing the jack and form into a position to exert pressure on the sole of a shoe supported on the jack, said position being a position of pressure. In order to hold the jack and form in the position of pressure during the time required to press the sole of a shoe, all such machines with which I am familiar are provided with means whereby the machine is thrown out of operation when the jack and form are brought into the position of pressure, in which position they remain until the machine is again thrown into operation by the operator. The duration of the pressure is thus dependent on the judgment of the operator, and as a consequence the soles are often not properly pressed, the form and jack being kept in the position of pressure so long as to distort the sole or not

long enough to cause the sole to take the desired shape or curvature.

One of the objects of my invention is to provide such a machine by which the duration of the pressure is controlled automatically; and to this end my invention consists in a machine provided with a sole-pressing form and a shoe-supporting jack, of mechanism operating automatically and continuously to bring the jack and form into a position of pressure to hold them in such position during the time required to press the sole of a shoe placed on the jack and thereafter to separate the jack and form to bring the jack into a position of clearance.

Direct-pressure sole-pressing machines of the prior art have been provided with two sole-pressing forms and two coöperating jacks arranged to act alternately in pressing the soles of shoes supported on the jacks, the arrangement being such that while one jack is in a position of pressure the other jack is in a position of presentation. By this arrangement the operator is enabled to remove the shoe previously acted upon from one jack and place another thereon while the sole of the other shoe is being pressed, thereby effecting a considerable saving in time. The jacks have, however, been constantly connected to their actuating mechanism or to each other, so that the operator after having removed a shoe from the jack in the position of presentation and placed another shoe thereon has been obliged to wait during the time required to bring said jack to its position of pressure and the other jack to its position of presentation. Moreover, as the machines are arranged to be thrown out of operation when either jack reaches its position of pressure and are only thrown into operation by an act of the operator, the speed at which the machines work is dependent entirely on the will of the operator.

Another object of my invention is to provide a machine of the type referred to in which the jacks and forms shall be so actuated that at no time during the operation of the machine will the operator be required to wait for certain movements to be completed before a shoe can be removed from or adjusted on one of the jacks.

Another object is to provide a machine of the type referred to in which the jacks and forms shall be so actuated that the operator will be obliged to keep pace with the machine in placing the shoes on the jacks and remov-

ing them therefrom, whereby the machine will be operated at its normal rate of speed and a maximum amount of work produced.

With these and other objects in view, as will appear hereinafter, my invention consists in the devices and combinations of devices and arrangements hereinafter described and claimed.

A preferred form of my invention is illustrated in the accompanying drawings, in which—

Figure 1 is a view in front elevation of a sole-pressing machine embodying the same. Fig. 2 is a view in side elevation of the machine shown in Fig. 1. Fig. 3 is a view of said machine in rear elevation, a portion of the frame being broken away to show one of the sole-pressing forms in section. Fig. 4 is a longitudinal sectional view of said machine on the line 4-4 of Fig. 1. Fig. 5 is a cross-sectional view on the line 5-5, Fig. 1, of the machine-frame. Fig. 6 is a detail sectional view on the line 6-6 of Fig. 1, showing one of the sole-pressing forms and one of the locking-cams; and Fig. 7 is a plan view of the table upon which the jacks are supported.

The machine illustrated in the drawings is similar in many respects to the sole-pressing machine disclosed in my Patent No. 627,034, dated June 13, 1899; but it is to be understood that I have shown my invention as applied to such machine for convenience of illustration only and that the invention might be applied to other machines and embodied in many different constructions.

Referring to the drawings, in which like characters of reference indicate like parts, 1 indicates the frame of the machine, having journaled in the rear lower portion thereof a driving-shaft 2, provided with a loose driving-pulley 3 and a worm 4. The worm 4 meshes with a worm-gear 5, secured to a horizontal shaft 6, journaled in the machine-frame at right angles to the driving-shaft 2. Securel to the shaft 6 is a worm 7, meshing with a large worm-gear 8, fast on a shaft 9, journaled in the machine-frame and having secured thereto the cams from which the operating parts of the machine are actuated, as will be hereinafter described.

11 designates the shoe-supporting jacks adapted to receive and hold suitable lasts 12, and 13 designates the sole-pressing forms. In the drawings two sole-pressing forms and two coöperating jacks are shown; but it will be understood that any desired number of forms and jacks might be employed. The jack may be of any convenient or common form suitable for holding a wooden or iron last or any suitable device for supporting a shoe after removal from the wooden last. The form may be of any suitable construction adapted to exert pressure upon the sole of a shoe supported on the jack and may be the rigid metallic form commonly used in

sole-leveling machines or the flexible pressing-pad used in sole-laying machines. According to my invention one or more of the jacks and forms are relatively actuated by mechanism operating automatically and continuously to bring a jack and form into a position of pressure, to hold them in such position during the time required to press the sole of a shoe placed on the jack, and thereafter to return the jack to a position of presentation. Any suitable mechanism for so actuating the jacks and forms may be provided. In the machine shown in the drawings a jack is moved horizontally from its position of presentation to a position directly beneath one of the sole-pressing forms, said position being a position of clearance. Thereafter the form is lowered in contact with the sole of the shoe supported on the jack, in which position it is locked. The jack is then pressed upward against the form into a position of pressure and held therein during the time required to press the sole of the shoe, after which the form is raised and the jack lowered to its position of clearance and then returned to its position of presentation, the mechanism for effecting these movements operating automatically and continuously until the jack is returned to its position of presentation.

The mechanisms for lowering the form and seating it against the sole of the shoe supported on the jack, for raising the form, and for raising and lowering the jack are substantially the same as the mechanisms for effecting these movements in the machine of the patent hereinbefore referred to; but inasmuch as these mechanisms are fully illustrated in the drawings forming a part of this application they will be briefly described herein. As shown in the drawings, each form 13 consists of a block provided with a metallic face-plate 14 of the desired shape or curvature and with a dovetail projection adapted to be received in suitable guideways 15 of a block 16 and to slide therein. The longitudinal position of the form with relation to the block 16 can be adjusted by means of an adjusting-screw 17, having a screw-threaded engagement with an upwardly-extending portion of the form and bearing against the end of the block 16. The form is locked in adjusted position by means of an arm or pawl 18, pivoted to the block 16 and arranged to swing downwardly over the end of the screw 17. The upper edges of the block 16 are provided with lateral arc-shaped flanges which engage suitable guideways of a cross-head 19, arranged to reciprocate vertically in suitable guideways in the upper portion of the machine-frame. By means of the connection above described between the block 16 and the cross-head 19 the pressing-form can rock, so as to conform to the shape of the last. The form is nor-

mally held in a horizontal position by means of coiled springs 20, connecting the block 16 with the cross-head 19. To the cross-head 19 is secured a vertical rod 21, the lower end 5 of which projects through a bearing 22 on the machine-frame and through which it is free to reciprocate. To the rod 21 is secured a rack 23, with which meshes a segmental gear 24, carried upon one arm of the bell-crank 10 lever 25, pivoted at 26 on the machine-frame, and the other arm of which carries a roll arranged to be engaged by a peripheral cam 27, secured to the shaft 9. The shape of the cam 27 is such that the cross-head 19 is allowed to descend of its own weight at the 15 proper time to bring the form 13 into contact with the sole of the shoe supported on the jack which is beneath the form and thereafter is raised through the bell-crank-lever 25, 20 gear 24, rack 23, and rod 21.

For locking the forms 13 to withstand the upward pressure of the jacks a shaft 28 is mounted in suitable bearings in the machine-frame above the cross-head 19, and upon said 25 shaft are secured cams 29. Also secured to the shaft 28 is a segmental gear 30, which meshes with a segmental rack 31, carried by the swinging lever 32, fulcrumed at 33 on the machine-frame, the lower end of said lever 30 being provided with a cam-roll arranged to be engaged by a peripheral cam 34, secured to the shaft 9. Around the shaft 28 is arranged a coiled spring 35, one end of which is secured to a collar fast on the shaft and the 35 other end of which engages the machine-frame, the arrangement of the spring being such that the spring tends to rotate the shaft to turn the cams 29 toward the front of the machine. When the cams are so turned, 40 they will contact with the cross-head 19 and lock the cross-head and form against upward movement. The shape of the cam 34 is such that through the connections above described the shaft 28 will be rotated at the 45 proper time to turn the cams 29 backward to release the cross-head 19 and allow it to be raised, as hereinbefore described. It will be noted that the releasing movement of cams 29 is positive, while their locking movement 50 is spring-controlled, so that the locking movement automatically varies in extent to provide for different elevations of the cross-head 19, caused by differences in the height of the last or thickness in the sole of the shoe, 55 upon which the form rests.

The jacks 11 are carried by a table 36, free to reciprocate vertically along suitable guideways 37, and for raising and lowering the table to bring the jacks into a position of pressure 60 the following mechanism is provided: Upon the lower side of the table is fulcrumed the upper member of a toggle-lever 38, the lower member of which is fulcrumed upon a vertically-movable cross-head 39, which is 65 also movable along the guides 37. To the

cross-head 39 are secured two rods 40, which extend downwardly through bearings 41 in a cross-head 42, through which said rods are free to reciprocate, being guided and held in position thereby. Between the cross-head 70 42 and the cross-head 39 is interposed a coiled spring 43, the lower end of which bears against the cross-head 42 and the upper end against a disk 44, upon which bears a bolt 45, having a threaded bearing in the cross-head 75 39. The rods 40 are capped below the guides or bearings 41 to prevent them from being drawn out when the cross-head 39 is raised. The above-described construction is such that by raising or lowering the bolt 45 the 80 initial compression of the spring 43 can be regulated—that is, the spring can be adjusted to exert more or less force tending to hold the cross-heads 39 and 42 separated. The cross-head 42 when the jacks are in the position of 85 pressure is arranged to bear upon an adjustable rest or stop 46, which, as shown, consists of a suitable bolt passing through a nut 47, resting on the lower cross-bar of the machine-frame. Stops 48, secured in the guideway 90 37, are provided, which limit the downward movement of the table 36. When the table 36 rests upon the stops 48 and the toggle 38 is straightened, the cross-head 39 will be moved downward until the cross-head 42 95 contacts with the stop or rest 46, when the resistance of the spring 43 will oppose further downward movement of the cross-head 39, and the table 36 will therefore be raised, and if one of the jacks has been brought beneath one of the forms the jack and form will be brought into a position of pressure. For operating the toggle-lever 38 a link 49 is provided pivoted at one end to the joint of the toggle-lever and at its other end provided with a fork straddling the shaft 9 and with a cam-roll engaging the groove of a cam 50, secured to the shaft 9.

The jacks 11, as shown, consist of blocks arranged to slide in suitable guideways 51, secured to the table 36, each jack being provided with suitable holes or openings 52 for receiving pins projecting downward from the lasts 12. For actuating the jacks the machine shown in the drawings is provided with an actuating mechanism common to all the jacks, and means are provided whereby either or all of the jacks can be connected and disconnected from the actuating mechanism. This jack-actuating mechanism is constructed as follows: Pivotedly mounted on a horizontal rock-shaft 53 at the rear lower portion of the machine-frame are two upwardly-extending levers 54, rigidly connected at their lower ends by means of a sleeve, as shown in Fig. 3, and connected at their upper ends by means of a rock-shaft 55, journaled therein. The right-hand lever 54, as viewed in Fig. 3, is provided with a cam-roll engaging the groove of a cam 56, secured 100 105 110 115 120 125 130

to the shaft 9, whereby the levers 54 are swung backward and forward upon their pivot 53 during the rotation of the shaft 9. Pivotally mounted on the rack-shaft 55 or on the lever 54 are forwardly-extending links 57, having pivoted at their forward ends hooked pawls or latches 58, arranged to engage projecting lugs 59 on the jacks 11. For guiding the links 57 during the backward and forward movements a slotted bracket 60 is secured to each side of the table 36, a headed pin projecting laterally from the forward end of each link engaging the slot in the bracket. Pivotally mounted on the table 36 in line with the path of movement of the latches 58 are hand-levers 61, the inner ends of which are provided with inclined portions 62, which when the levers are swung into a position to bring such portions into the path of movement of the latches 58 engage the inclined forward ends of the latches and raise them out of engagement with the projections 59 of the jacks. By this construction it will be seen that both jacks can be connected to their actuating mechanism, so as to be moved simultaneously, or either one of the jacks so connected, the other jack remaining disconnected. It will also be seen that each jack will be automatically disconnected from its actuating mechanism when brought into its position of presentation if the hand-levers 61 are placed in the proper position. When the jacks are operated simultaneously, it is desirable that the operation of the machine be stopped when the jacks are returned from the position of pressure to the position of presentation in order to give the operator time in which to remove the shoes from the jacks and place other shoes thereon, and when the jacks are operated alternately it is desirable to stop the operation of the machine when either of the jacks is returned from its position of pressure to its position of presentation if the operator has not had time in which to remove the shoe previously acted upon from the other jack and to replace it by another. A convenient means for so stopping the operation of the machine is shown in the drawings and will now be described.

The loose driving-pulley 3 is clutched to the driving-shaft 2 during the operation of the machine by a clutch member 63, splined on the shaft and forced into contact with the hub of the loose pulley by a coiled spring 630. The clutch member 63 is provided with an inclined projection 64, (see Figs. 1 and 3,) which is arranged to contact with an arm 65, secured to the rock-shaft 53, and force the clutch member out of engagement with the pulley when the arm is brought into the path of the projection. The rock-shaft 53 has secured thereto a laterally-projecting arm 650, (see Fig. 2,) which is connected, by means of a rod 66, to an arm 67, secured to the rock-shaft 55. Also secured to the rock-shaft 55 are two arms 68, and from each arm 68 a rod 69 extends through a lug 70 on the upper side of a link 57 and through the upturned end 71 of a latch 58. The forward end of each rod 69 is headed, as at 72, and a coiled spring 73, surrounding the rod, is interposed between the lug 70 and the upturned end 71 of the latch. Surrounding the rod 66 is a coiled spring 74, the upper end of the spring bearing against a lug on one of the levers 54 and the lower end of the spring bearing against the collar 75, adjustably secured to the rod. Each spring 73 is stronger than the spring 74, so that when either spring 73 is allowed to act on a rod 69 the rod 66 will be raised against the tension of spring 74 and through the arm 650 and rock-shaft 53 move the arm 65 away from the path of the projection 64 of the clutch member 63. When, however, both latches 58 are raised into the position shown in Fig. 2 by the inclined portions 62 of the hand-levers 61, the upwardly-projecting portions 71 of the latches will compress the springs 73 and at the same time move away from the heads 72, thereby freeing the rods 69 from the pressure of the springs 73 and allowing the spring 74 to depress the rod 66 and bring the arm 65 into the path of the lug 64. By the above-described arrangement it will be seen that the jacks are automatically disconnected from their actuating mechanism when brought into the position of presentation from a position of pressure and that simultaneously the machine is thrown out of operation. It will also be seen that when one of the hand-levers 61 is moved to allow a latch 58 to engage the projection 59 of a jack, and thereby connect the jack with its actuating mechanism, the machine is simultaneously thrown into operation.

In the practical operation of the machine it is intended that the jacks be actuated alternately, a shoe previously acted upon being removed from one jack and another shoe placed thereon while the other jack is being brought into a position of pressure and returned to its position of presentation. The normal position of the hand-levers 61 will be with their inclined portions 62 in the path of movement of the latches 58. By keeping the hand-levers in this position the machine will be automatically stopped as each jack is returned to its position of presentation. The actuating-cams are so constructed and timed that when a jack has been connected to its actuating mechanism and the machine thrown into operation by a movement of a lever 61 the jack and its co-operating form will be actuated to bring the jack and form into a position of pressure to hold them in such position during the time required to press the sole of the shoe placed on the jack and thereafter to return the jack to its position of presentation. By so actuating the jack and form the duration of the pressure is

controlled entirely by the machine, and the sole of the shoe is properly pressed. During the operation of the machine in pressing the sole of a shoe placed upon one of the jacks 5 and returning the jack to its position of presentation the operator can remove the shoe previously acted upon from the other jack and place another shoe thereon, and immediately the first-mentioned jack returns to its position of presentation can connect the jack upon which the shoe has been placed with its actuating mechanism and proceed to remove the shoe from the first-mentioned jack without waiting for any movements of 10 the machine to be completed. The entire time of the operator can thus be employed in the removal from and adjustment of the shoes on the jacks. The machine should be so speeded that the time required for completing the pressing of the sole of a shoe placed upon one of the jacks and returning the jack to its position of presentation is that required by the operator in removing a shoe from the other jack and placing another shoe 15 thereon. The operator is thus obliged to keep pace with the machine, as otherwise the machine will come to rest for an unreasonable length of time with both jacks in the position of presentation, and thus call attention 20 to the fact that the operator is not keeping pace with the machine.

It is believed that the operation of the machine above described has been sufficiently indicated to be readily understood, and further description thereof is deemed unnecessary.

Having thus described my invention, I claim as new and desire to secure by Letters Patent—

40 1. A sole - pressing machine, having, in combination, a shoe-supporting jack, a sole-pressing form, and mechanism operating automatically and continuously to impart a relative vertical movement to the jack and form to bring the jack and form into a position of pressure, to hold the jack and form in said position during the time required to press the sole of a shoe placed upon the jack, and thereafter to separate the jack and form 45 to bring the jack into a position of clearance, substantially as described.

50 2. A sole - pressing machine, having, in combination, a shoe-supporting jack, a sole-pressing form, and mechanism operating automatically and continuously to impart a relative vertical movement to the jack and form to bring the jack and form into a position of pressure, to hold the jack and form in said position during the time required to press the sole of a shoe placed upon the jack, and thereafter to return the jack to its position 55 of presentation, substantially as described.

60 3. A sole - pressing machine, having, in combination, a plurality of shoe-supporting

jacks, a plurality of pressing-forms coöperating respectively therewith, mechanism for relatively actuating the jacks and forms to cause each jack and its coöperating form to press the sole of a shoe placed on the jack, 70 comprising means for imparting relative vertical movements to each jack and form to produce pressure and clearance, means controlled by the operator for connecting each jack with said actuating mechanism, and automatic 75 means for disconnecting each jack therefrom, substantially as described.

4. A sole - pressing machine, having, in combination, a plurality of shoe-supporting jacks, a plurality of pressing-forms coöperating respectively therewith, mechanism for relatively actuating the jacks and forms to cause each jack and its coöperating form to press the sole of a shoe placed on the jack, 80 comprising means for imparting relative vertical movements to each jack and form to produce pressure and clearance, and means for connecting each jack with said actuating mechanism having provision for throwing said mechanism into operation, substantially as 85 described.

5. A sole - pressing machine, having, in combination, a plurality of shoe-supporting jacks, a plurality of pressing-forms coöperating respectively therewith, mechanism operating automatically and continuously to impart a relative vertical movement to each jack and form when connected therewith to bring the jack and form into a position of pressure, to hold the jack and form in said position during the time required to press the sole of a shoe placed upon the jack, and thereafter to return the jack into its position of presentation, and means for connecting and disconnecting each jack and said actuating 95 mechanism, substantially as described.

6. A sole - pressing machine, having, in combination, a plurality of shoe-supporting jacks, mechanism for imparting to the jacks rectilinear reciprocating movements to bring them from a position of presentation to a position of clearance and to return them to a position of presentation, means for connecting and disconnecting each jack and said mechanism, and mechanism for imparting to each 105 jack and form relative vertical movements to bring the jack and form into a position of pressure and to separate the jack and form to bring the jack into a position of clearance, substantially as described.

7. A sole - pressing machine, having, in combination, a plurality of shoe-supporting jacks, a plurality of forms coöperating respectively therewith, mechanism acting to bring each jack and form when connected therewith into a position of pressure, to separate the jack and form to bring them into a position of clearance, and to return the jack to a position of presentation, means for throwing each jack and its coöperating form into and 120 125 130

out of operative connection with said actuating mechanism, and means acting automatically to throw said actuating mechanism out of operation when the jack is in its 5 position of presentation and its coöperating form is in its position of clearance, substantially as described.

8. A sole - pressing machine, having, in combination, a plurality of shoe-supporting 10 jacks, a plurality of forms coöperating respectively therewith, mechanism acting to bring each jack and form into a position of pressure, to separate the jacks and forms to bring them into a position of clearance, and to return the jacks to a position of presentation, and means acting automatically to throw 15 said actuating mechanism out of operation when one of the jacks is in its position of presentation and all the forms are in their position of clearance, substantially as described.

9. A sole - pressing machine, having, in combination, a plurality of sole - pressing forms, a plurality of shoe-supporting jacks coöperating respectively therewith, a vertically - reciprocating supporting - table common to all the jacks and along which each jack is independently movable from a position of presentation to a position of clearance, and means for actuating the table and 25 jacks, substantially as described.

10. A sole - pressing machine, having, in combination, a plurality of shoe-supporting jacks, a plurality of sole - pressing forms coöperating respectively therewith, swinging levers for imparting to said jacks a rectilinear 30 movement from a position of presentation to

a position of clearance, links and latches connecting the levers and jacks, and means for automatically actuating the latches to disconnect the jacks when the jacks are returned 40 to a position of presentation, substantially as described.

11. A sole - pressing machine, having, in combination, a plurality of shoe-supporting 45 jacks, a plurality of sole - pressing forms coöperating respectively therewith, and mechanism for relatively actuating the jacks and forms to press the soles of shoes supported upon the jacks and to return the jacks to a position of presentation having provision for 50 actuating each jack separately or all the jacks simultaneously at the will of the operator, substantially as described.

12. A sole - pressing machine, having, in combination, a plurality of shoe-supporting 55 jacks, a plurality of sole - pressing forms coöperating respectively therewith, mechanism acting to impart to each jack and its coöperating form relative vertical movements to produce pressure and clearance and to return the jack to its position of presentation while the other jacks remain in a position of presentation, and means acting automatically to throw said mechanism out of operation when all the jacks are in a position of presentation, substantially as described.

In testimony whereof I affix my signature in presence of two witnesses.

ERASTUS E. WINKLEY.
